(57) **CLAIM**

The ornamental design for a vehicle wheel, toy vehicle wheel, and/or replicas thereof, as shown and described.

DESCRIPTION

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.

The drawing of FIG. 5 forms no part of the claimed design.
